DESIGN FOR A TOP BURNER ASSEMBLY
FOR GAS COOKSTOVESHerbert M. Reeves, Kankakee, Ill., assignor to
Florence Stove Company, Gardner, Mass., a
corporation of Massachusetts

Application May 3, 1946, Serial No. 129,243

Term of patent 7 years

(Cl. D81—10)

To all whom it may concern:

Be it known that I, Herbert M. Reeves, a citizen of the United States, residing at Kankakee, in the county of Kankakee and State of Illinois, have invented a new, original, and ornamental Design for a Top Burner Assembly for Gas Cookstoves, of which the following is a specification, reference being had to the accompanying drawings, forming a part thereof.

Figure 1 is a top view of a top burner assembly for gas cookstoves embodying my new design.

Fig. 2 is a side elevational view of the burner assembly.

Fig. 3 is a front elevational view of the burner assembly.

Fig. 4 is an elevational view showing the opposite side of the burner assembly from Fig. 2.

Fig. 5 is a rear elevational view of the burner assembly.

Fig. 6 is a perspective view of the burner assembly.

I claim:

The ornamental design for a top burner assembly for gas cookstoves, substantially as shown.

HERBERT M. REEVES.
